(57) **CLAIM**

The ornamental design for a filling tip attachment as shown and described.

DESCRIPTION

FIG. 1 is a front perspective view of a filling tip attachment according to a first embodiment.

FIG. 2 is a rear perspective view of the filling tip attachment of FIG. 1.

FIG. 3 is a left-side view of the filling tip attachment of FIG. 1.

FIG. 4 is a right-side view of the filling tip attachment of FIG. 1.

FIG. 5 is a front view of the filling tip attachment of FIG. 1. FIG. 6 is a rear view of the filling tip attachment of FIG. 1. FIG. 7 is a top view of the filling tip attachment of FIG. 1; and,

FIG. 8 is a bottom view of the filling tip attachment of FIG. 1.

The portions of the filling tip attachment shown in broken lines are included for the purpose of illustrating environment and form no part of the claimed design. The portions of the filling tip attachment shown in broken lines having unequal length segments illustrate the boundary of the claimed design and form no part of the claimed design.

1 Claim, 4 Drawing Sheets
